UNITED STATES PATENT OFFICE.

HERSCHEL V. SANFORD, OF MILLEDGEVILLE, GEORGIA.

CHECK-FILE.

SPECIFICATION forming part of Letters Patent No. 247,420, dated September 20, 1881.

Application filed June 21, 1881. (No model.)

To all whom it may concern:

Be it known that I, HERSCHEL V. SANFORD, of Milledgeville, in the county of Baldwin and State of Georgia, have invented certain useful 5 Improvements in Check-Files, of which the following is a specification.

Figure 1, Sheet 1, is a front elevation of a part of my improvement. Fig. 2, Sheet 1, is a sectional side elevation of the same, taken 10 through the line *x x*, Fig. 1. Fig. 3, Sheet 2, is a rear elevation of the same.

Similar letters of reference indicate corresponding parts.

The object of this invention is to promote 15 accuracy in receiving and filing cash-checks and other memoranda.

The invention consists in constructing a check-file with a supporting-frame to be attached to the cashier's desk, and provided with 20 shelves, the separable file, the hinged bars for covering the ends of the files, the springs and keeper for holding the hinged bars suspended, the rod and lever for tripping the suspended bars, and the chains for raising the bars, all 25 constructed and operating as will be herein-after fully described.

There are two upright bars, which are connected at their upper ends by a cross-bar, B, attached to their forward sides, and connected at a little 30 distance from their upper ends by cross-bars C D, the rear bar, D, being a little higher than the forward bar, C. To the uprights A are attached blocks or brackets E, which are designed to rest upon the forward part of the top 35 of the cashier's desk. To the uprights A, a little below the top of the cashier's desk, are attached brackets F, to which are attached inclined tables or shelves G, to serve as desks for the salesmen to make their memoranda 40 upon. To the brackets E are attached inclined shelves H, which have cleats attached to their upper sides, at or along the edges, to form a groove for the board I. To the board I are attached, at suitable distances apart, wire 45 rods J, to serve as files to receive the checks or other memoranda to be filed. One end of the board I is grooved and rests against a tongued end block, K, secured to the shelf H. The other end of the file-board I rests against 50 a block, L, which slides upon the shelf H and is held forward by a spring, M. With this

construction, when the files are full, or when the business of the day is finished, the cashier can remove the board I, the file-rods J, and the memoranda, and place them in the safe or 55 other secure place until the said memoranda can be entered in the books, or otherwise disposed of.

To a rod, N, attached to the uprights A, are pivoted a number of bars or levers, O, which 60 are numbered consecutively, or are marked with the same numbers, letters, or words that distinguish the salesmen or cash-boys. The hinged arms, bars, or levers O rest upon the cross-bar D so as to be just above the ends of 65 the files J. The other or short arms of the levers O project in front of the frame A B C D, and to them are attached springs P, which pass up between the bar B and the bar Q attached to the said bar B, to serve as keepers 70 for the wire springs P. Upon each of the springs P, near its upper end, is formed an offset, R, as shown in Fig. 2. With this construction, when an arm, bar, or lever, O, is raised to uncover a file, J, the corresponding 75 spring, P, is drawn downward until the offset R catches upon the bar or keeper Q and holds the bar O raised. The bars O are lowered by the cashier by operating the lever S. The lever S is pivoted to the upright bar A, 80 and its forward end has a slot or loop formed in it to receive a wire or rod, T, the end parts of which are bent inward and are hinged to the ends of the rod N. When the lever S is operated the wire T is raised and pushes all 85 the wire springs P forward and allows the levers O to drop. To the forward end of each lever O is attached the upper end of a short chain, U. The lower ends of the chains U are attached to spring-levers V. The forward ends 90 of the levers V are attached to the shelf G, and the said levers are kept from rising too high by a wire keeper, W, the ends of which are attached to the said shelf.

If desired, the spring-levers V and the keeper 95 W can be omitted. In this case the chains U can be shortened and knobs or handles attached to them. This arrangement leaves a space between the shelves G and H free, so that the salesmen can pass their memoranda 100 through the said space.

In using the mechanism the salesman passes

his money and check to the cashier, and then forces downward the lever W, that bears his number, letter, or other distinguishing mark, or draws the chain U downward. The downward movement of the chain U raises the corresponding lever, O, away from the file, so that the cashier cannot make a mistake and put the check upon the wrong file. As soon as the cashier has filed the check he touches the lever G and the bar O again drops into place.

Having thus fully described my invention, I claim as new and desire to secure by Letters Patent—

1. A check-file constructed substantially as herein shown and described, consisting of the frame A B C D, provided with the shelves G H, the file I J, the hinged arms O, the springs P and keeper Q, the trip-rod T and lever S, and the chains U, as set forth.

2. In check-files, the consecutively-numbered levers O, hinged to rod N, resting with their long arms on the cross-bar D just above the files, and having the short arms connected by

chains U and spring-levers V with the shelves E, as and for the purpose specified.

3. In a check-file, the combination, with the frame A B C D and the hinged bars O, of the springs P, having offsets R, and the keeper Q, substantially as herein shown and described, whereby the said hinged arms will be held in place when raised from the files J, as set forth.

4. In a check-file, the combination, with the frame A B C D, the hinged arms O, the springs P, and the keeper Q, of the trip-rod T and the lever S, substantially as herein shown and described, whereby the suspended bars O can be instantly released, as set forth.

5. In check-files, the combination of the shelf H, the block L, sliding upon said shelf and held forward by a spring, M, the block K, secured to the shelf, and the end grooved board I, resting against the block L, as described.

HERSCHEL VIRGIL SANFORD.
